UNITED STATES PATENT OFFICE.

CHARLES K. STOCKLAND, OF MINNEAPOLIS, MINNESOTA.

GRADING-MACHINE.

1,247,895.

Specification of Letters Patent.

Patented Nov. 27, 1917.

Application filed December 17, 1914. Serial No. 877,636.

To all whom it may concern:

Be it known that I, CHARLES K. STOCKLAND, a citizen of the United States, residing at Minneapolis, in the county of Hennepin and State of Minnesota, have invented certain new and useful Improvements in Grading-Machines, of which the following is a specification.

My invention relates to grading machines, particularly of the type that is operated by traction engines, and has for its object to provide improved draftbar means suitable for offsetting the point of attachment to the traction engine or other device for drawing the grader. This offsetting means is manually controlled by means operative wholly within the frame of the grader.

The full objects and advantages of my invention will appear in connection with the detailed description thereof and are particularly pointed out in the claims.

In the drawings, illustrating the application or my invention in one form,—

Figure 1 is a side elevation of a grading machine embodying my improvements. Fig. 2 is a plan view of the front part of the grader. Fig. 3 is a bottom view of the front part of the grader drawn to a larger scale with parts broken away and parts in section. Fig. 4 is an enlarged sectional view of a portion of the frame looking toward the front. Fig. 5 is a longitudinal sectional elevation through the draftbar connection and driving mechanism. Fig. 6 is a plan view of a portion of the scraper frame showing the drawbar secured in rigid alignment with the frame.

As illustrated in Fig. 1, my grading machine comprises a frame 10 supported by front and rear wheels 11 and 12, back platform 13, scraper blade 14 carried by draftbars 15 which are suspended by links 16 from rock shafts 17, having on their ends worm gears 18 operated by hand worm wheels 19, all of which is common and well-known in the grading machine art. As described and claimed in my co-pending application, Serial Number 835,797, filed May 2, 1914, I connect the front end of the draftbars to slide vertically along a vertical post 20, which, in this instance, is a hollow pipe for purposes which will later appear. The scraper is quickly lifted by means of an elbow lever 21 connected with the front end of draftbars 15, and another elbow lever 22 connected with pieces 32 slidable on arc

members 64, which pieces form the journal support for rock shafts 17, the two elbow levers 21 and 22 being simultaneously operable by a hand lever 23 through link connections 24 and 25 to lift the entire draftbar mechanism and the scraper 14 connected therewith bodily in a vertical direction, all as described and claimed in my aforesaid application. The draftbar mechanism 15 includes a collar 33 having a roller 34 journaled in the forward part thereof for engagement with the upright 20, as best shown in Fig. 5.

The front part of frame 10 has secured thereto by means of angularly-disposed arms 26 and 27 a bolster plate 28 which rests upon a similar bolster plate 29 rigidly connected by means of arms 30 and 31 with the front axle, all as best shown in Fig. 4. The collar 33 of draftbar 15 normally rests upon the bolster plate 28 when the draftbars and scraper are in lowered or operative position. A drawbar 35 extends forwardly from the post 20 upon which it is journaled immediately below the bolster plate 29. A shaft 36 extends through the center of post 20 and has secured to the upper end a bevel gear 37, and has secured to the lower end a bevel gear 38 which comes below a casting 39 fast on drawbar 35. By this means the drawbar is held positioned upon the lower end of post 20, below bolster plate 29. An arc member 40 is secured at its ends to the angular arms 30 and 31 and is provided on its under surface with a series of pins 41, forming in effect a segment rack on said arc member. The drawbar 35 has secured thereto an arm 42 extending rearwardly above the arc member 40. The arm 42 carries a plate 43 which has secured thereto a plurality of lugs 44 embracing the edges of arc member 40 so as to form a slide thereon. Secured to plate 42 and lugs 44 is a housing 45 in which is journaled a short shaft 46 carrying inside of the housing a worm disk 47 provided with a face worm 48 engaging between the pins 41, as best shown in Fig. 3. The shaft 46 carries a bevel gear 49 outside of housing 45, which meshes with a bevel gear 50 on a shaft 51 journaled in an extension 52 from housing 45 and an extension 53 of casting 39. On the shaft 51 is a bevel gear 54 meshing with bevel gear 38 on the vertical shaft 36. A shaft 55 is journaled at its rear end to a standard 56 and at its forward end in a bracket 57, said shaft be-

ing provided with a bevel gear 58 meshing with bevel gear 37 on vertical shaft 36. By means of a hand wheel 59 positioned on the end of shaft 55 adjacent the platform 13 said shaft may be rotated by the operator. This will result, through the connections described, in turning the worm 48, which, by engagement with the pins 41 on segment 40, will have the effect of oscillating the drawbar 35 relative to the axle 32, said axle being otherwise held fixed relative to the drawbar by means of the pins 41 and worm 42. If the drawbar is free to oscillate, as in Figs. 2 and 3, it will be turned relative to 10 the axle, and the axle and front wheels will respond to lateral movements of the drawbar. As shown in Fig. 6, the drawbar 35 is rigidly connected to frame 10 by means of brace rods 60 and 61, said drawbar being 15 thereby held in the longitudinal central line of the machine. Rotation of the hand wheel 59 and parts connected thereto will, under these conditions, operate to oscillate the axle 32 and the front wheels 11, by which means 20 the scraper may be steered independently of 25 the drawbar 35.

The advantages of this organization will be apparent. In the ordinary use of the construction, as indicated in Figs. 2 and 3, 30 the drawbar may be turned so as to extend forwardly to one side of the line of draft, where the same may be connected with the traction engine or other pulling means. The advantage of this is, that the engine 35 may run upon the level central portion of a road while the scraper will be down on the sloping side-portion of the road where the scraper must ordinarily operate. The turning of the drawbar under these circumstances is always about the draft post 20 as 40 a center, so that the draft strain is always directly carried to this draft post. By reason of the fact that the oscillation of the drawbar is about the draft center, it is an 45 easy matter for the operator to move the drawbar when the machine is in operation and the drawbar subject to heavy strain. It will be apparent that the operator by manipulation of the hand wheel 59 can so 50 oscillate the drawbar 35 and the tongue 64 connected therewith as to hold the scraper to its work at the side of the road while the traction engine which pulls the grader runs along the top level. Under some conditions 55 better results may be obtained by holding the drawbar 35 rigid, as indicated in Figs. 1 and 6, in which case the wheels 11 become ordinary steering wheels which are oscillated and controlled by the shaft 55 and 60 hand wheel 59.

I claim:

1. In combination with the frame and front axle of a grading machine, a draft post mounted in said frame and providing a point of pivotal attachment of the frame 65 with the axle, a drawbar pivoted to said draft post and having a portion thereof extending rearwardly of the same, a holding device including a rigid sector co-operating with said rearwardly-extended portion to 70 hold the drawbar and axle in fixed relative position, and means including a shaft extending through the draft post to operate the holding means to oscillate the drawbar.

2. In combination with the frame and 75 front axle of a grading machine, a drawbar, common means pivotally connecting said drawbar and axle with the frame, means holding said drawbar and axle in fixed relative position, and means under the control 80 of the operator including a shaft extending through the center of oscillation of said drawbar and axle for operating the holding means to cause the same to oscillate the drawbar and axle relatively.

3. In combination with the frame of a grading machine, a tubular draft post mounted on said frame, a front axle journaled on said draft post for oscillatory movements in a horizontal plane, a drawbar 90 pivoted to said draft post, means holding said drawbar and axle in fixed relative position, and means under the control of the operator including a shaft extending through the draft post in the axis of oscillation of the axle and drawbar for operating said holding-means to cause the same to oscillate the drawbar and axle relatively.

4. In combination with the frame of a grading machine, a tubular draft post 100 mounted on said frame, a front axle journaled on said draft post for oscillatory movements in a horizontal plane, a drawbar pivoted to said draft post, a segment rack connected with the axle, a worm engaging 105 said rack and normally holding the drawbar and axle in fixed relative position, a shaft extending through said tubular member and the axis of oscillation of the axle and drawbar, gear mechanism connecting 110 said shaft with the worm, and a hand wheel having operative connection with said shaft for rotating the shaft and worm to oscillate the drawbar and axle relatively.

In testimony whereof I affix my signature 115 in presence of two witnesses.

CHARLES K. STOCKLAND.
